CLAIM

The ornamental design for a stool, as shown and described.

DESCRIPTION

FIG. 1 is a perspective view of a stool according to the present disclosure, shown in a raised position;

FIG. 2 is a right side view of the stool in the raised position;

FIG. 3 is a left side view of the stool in the raised position;

FIG. 4 is a front elevation view of the stool in the raised position;

FIG. 5 is a rear elevation view of the stool in the raised position;

FIG. 6 is a top view of the stool in the raised position;

FIG. 7 is a bottom view of the stool in the raised position;

FIG. 8 is perspective view of the stool shown in a lowered position;

FIG. 9 is a right side view of the stool in the lowered position;

FIG. 10 is a left side view of the stool in the lowered position;

FIG. 11 is a front elevation view of the stool in the lowered position;

FIG. 12 is a rear elevation view of the stool in the lowered position;

FIG. 13 is a top view of the stool in the lowered position; and,

FIG. 14 is a bottom view of the stool in the lowered position. The broken lines in the drawings represent portions of the stool that form no part of the claimed design.

1 Claim, 8 Drawing Sheets
